GEORGE B. GRAFF, OF NEWTON CENTER, AND ROBERT A. STEWART, OF WATERTOWN, MASSACHUSETTS, ASSIGNORS TO GEORGE B. GRAFF COMPANY, OF CAMBRIDGE, MASSACHUSETTS, A CORPORATION OF MASSACHUSETTS

SIGNAL DEVICE

Application filed August 19, 1930. Serial No. 476,290.

This invention relates to clips adapted to be attached to the margins of cards, files or other indexed sheets and to serve as a signal identifying the subject matter on the sheet or supplying other information pertaining thereto. The principal object of the invention is to provide an improved slip signal of simple and durable construction which may be readily attached to or removed from the sheet and which, when attached, is secured against casual separation or misplacement.

Recommended embodiments of the invention are illustrated in the accompanying drawings, in which:

Fig. 1 is a front view of a card having the improved signal clip attached thereto;

Fig. 2 is a rear view thereof;

Fig. 3 is an enlarged section on the line 20 3—3 of Fig. 1;

Fig. 4 is a perspective view of the clip;

Fig. 5 is an edge view illustrating the preferred method of attaching the clip to a card; and

Fig. 6 is a face view of a modified form of clip.

The improved device comprises a spring clip formed of resilient sheet metal folded transversely at 7 to furnish two legs 8 and 9 respectively which are normally urged toward each other by the resiliency of the clip. The free ends of the legs 8 and 9 are preferably rounded at their lower ends as at 10 and 11.

The structure is preferably made with one leg 8 flat, while the other leg 9 is provided with inwardly struck depressions or indentations 12 and 13 disposed in spaced relation and normally contacting with the inner face of the leg 8, thereby contacting the tip portion 11 with said face. Insertion of a card or sheet is readily accomplished by pressing together the intermediate portion of the legs 8 and 9 as illustrated in Fig. 5, thereby permitting the clip to be easily slipped endwise over the edge of a card or sheet 14.

When thus attached to the card, as shown in Figs. 1 to 3, the portions 11, 12 and 13 engage the card and frictionally and firmly

grip and retain the clip thereon against relative angular movement or casual detachment. The outer face of the leg 8 of the clip may be colored or otherwise marked to serve as a suitable signal, as indicated for example by the red color of Fig. 1; or one of said portions, for example the portion 15 of the modified clip shown in Fig. 6, may have a window aperture 16 to display a signal marked on the card itself, as the numeral "4".

A signal clip constructed as above described is simple and inexpensive to manufacture, easily and securely affixed to an index sheet, and adapted to carry or display a variety of signals. The signal clip is clearly visible even though the sheet is assembled with others in a book or filing system; yet the clip does not project appreciably beyond the edge of the card and is thus less likely to be dislodged or damaged.

We claim:

1. A signal device for index systems, comprising a pair of legs of thin resilient material adapted to receive and grip a card therebetween, said legs being connected together at one end of said clip and in contact adjacent their free ends, said device having two longitudinally spaced indentations and each of said indentations adapted to grip a card against the inner face of the opposing leg, said indentations being spaced apart and with one indentation sufficiently close to the free end of said leg to permit the intermediate portion of the device between said indentations to be pinched between the fingers to sufficiently separate the normally contacting free ends of said legs to readily permit the insertion of a card therebetween, the indentation adjacent the free end acting as a fulcrum for such purpose.

2. A signal device for index systems, comprising a pair of legs of thin resilient material adapted to receive and grip a card therebetween, said legs being connected together at one end of said clip and in contact adjacent their free ends, one leg having two longitudinally spaced indentations on the inner side thereof, adapted to grip a card against the inner face of the opposing leg,

- said indentations being spaced apart and with one indentation sufficiently close to the free end of said leg to permit the legs between said indentations to be pinched between the fingers to sufficiently separate the normally contacting free ends of said legs to readily permit the insertion of a card therebetween, the indentation adjacent the free end acting as a fulcrum for such purpose.
- 10 3. A signal device for index systems, comprising a pair of legs of thin resilient material adapted to receive and grip a card therebetween, said legs being connected together at one end of said clip and in contact adjacent their free ends, one leg having two transverse ridges on the inner side thereof, adapted to grip a card against the inner face of the opposing leg, said ridges being spaced apart and with one ridge sufficiently close
- 15 to the free end of said leg to permit the leg between said ridges to be pinched between the fingers to sufficiently separate the normally contacting free ends of said legs to readily permit the insertion of a card therebetween, the ridge adjacent the free end acting as a fulcrum for such purpose.
